UNITED STATES PATENT OFFICE

CARRIE VAN WIE, OF CHICAGO, ILLINOIS

CURTAIN PROTECTOR

Application filed September 29, 1931. Serial No. 565,836.

This invention relates to certain novel improvements in curtain protectors, and has for its principal object the provision of an improved construction of this character which will be highly efficient in use and economical in manufacture.

It is an object of this invention to provide an improved device for protecting curtains, shades, drapes and the like against being soiled and damaged by the lower end portion of the curtain, or like article, being blown or flapped through the window when the sash is raised.

Another object of the invention is to provide an improved extensible curtain protector which may be accommodated to sashes of various widths.

A further object resides in the provision of unique means by which to readily attach the protector to, and to detach it from, the sash.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary front elevational view of a conventional window showing the invention in working position;

Fig. 2 is a perspective view of the invention;

Fig. 3 is a sectional view on line 3—3 in Fig. 1; and

Fig. 4 is a perspective view of a part of the invention.

In the drawings, which illustrate a preferred and practical embodiment of the invention, 10 indicates generally a window frame which includes a sill 11, while 12 indicates generally a lower sash slideable in the frame, and which includes the stiles 13 and bottom rail 14. 15 includes a curtain which is suspended by suitable means, not shown. As is well known, when the sash 12 is raised so that the rail 14 is above the sill 11 the lower end portion of the curtain will frequently flap in and out of the space between the sill and the rail 14. To prevent this I provide my

improved curtain protector now to be described.

The present invention includes a pair of similar clamping arms 16 and 17 in each of which is provided a channel slot 18 and these slots slidably receive the bars 19 and 20 that are extensible into and out of the arms 16 and 17.

The arms 16 and 17 are hinged together at one end by a hinge 21, Fig. 4, which includes a pair of brackets 22 that receive the ends of the arms and are secured thereto by suitable connecting elements 23. The hinge 21 includes a pintle 24 that includes a hooked portion 25 for attachment to an eyelet 26 fastened in one of the stiles 13.

The end portion 27 of bar 20 carries a hinge 28 that is similar to the hinge 21 and this hinge 28 includes a pair of brackets 29 and 30 that are similar to the brackets 22. 70 However, bracket 29 is permanently secured to the portion 27 while bracket 30 is in the nature of a clamp hinged to bracket 29 and provided with an aperture 31 that is adapted to receive a headed element 32 fastened in the end portion 33 of bar 19. The pintle of hinge 28 includes a hooked portion 34 adapted to be engaged in an eyelet 35 carried by the other rail 13. 75

In use, the hooked portions 25 and 34 will be fastened to the eyelets 26 and 35 so that the device will be mounted on the sash for movement therewith. The lower end portion of the curtain will then be inserted between the arms 16 and 17, the bars 19 and 20 being extended to fit the width distance between the hooked portions 25 and 34 to the distance between the eyelets 26 and 35. The bracket portion 30 is then swung over the end of bar portion 33 with the head of element 32 received in aperture 31 whereby the arms 16 and 17 will clamp the lower end portion of the curtain therebetween so that the same will be prevented from flapping through the open window. Since the lower end portion of the curtain will thus move with the sash the latter may be raised and lowered and will carry the lower end portion of the curtain therewith so that the sash may be raised to any desired extent and yet 100

the curtain be prevented from flapping through the opened window. The device may be removed from the sash, when desired, by removing the hooks 25 and 34 from the eyelets 26 and 35.

5 Other equivalent means may be used for mounting the clamping arms on the sash without departing from the purview of this invention and the description of the hooks and eyelets for this purpose is not to be considered a limitation.

10 The lower end portion of a shade, drape or the like may also be clamped between the arms in the manner in which the curtain is clamped as hereinbefore described.

15 While I have illustrated and described a preferred use of the invention as a protective device for the lower end of a curtain it may be used for hanging curtains, drapes or shades. Thus by placing the upper end portion of the curtain between arms 16 and 17 and closing the clasp a curtain or the like may be suspended while being readily removable when it is necessary to clean or dust the curtain. Moreover, the eyelets or like 20 means may be placed in the window casement, in this use of the invention, so that the device will be stationarily mounted.

25 While I have illustrated and described the preferred form of construction for carrying my invention into effect, this is capable of variation and modification without departing from the spirit of the invention. I, therefore, do not wish to be limited to the 30 precise details of construction set forth, but desire to avail myself of such variations and modifications as come within the scope of the appended claims.

35 Having thus described my invention, what I claim as new and desire to protect by Letters Patent is:

1. A device of the character described, comprising a pair of clamping members adapted to receive therebetween the lower 40 end portion of a curtain or the like, means to clamp said members together and said curtain portion therebetween, and means to mount said members on a window sash.

2. A protective device of the character described comprising a pair of extensible clamping members adapted to receive therebetween the lower end portion of a curtain or the like, means to clamp the members together and the curtain portion therebetween, and means to mount said members on a window sash so that the curtain portion will move with the sash, said members being extensible to accommodate them to the width of the sash.

3. A protective device for curtains and the like comprising a pair of clamping members, means hingedly connecting said members together at one end, whereby when said members are spread apart the lower end portion 55 of a curtain may be inserted therebetween, a

clamping structure to detachably connect the other ends of said members together to clamp said curtain portion therebetween, and means to mount said members on a window sash for movement therewith.

4. A protective device for curtains and the like comprising a pair of extensible clamping members, means hingedly connecting said members together at one end, whereby when said members are spread apart the lower end portion of a curtain may be inserted therebetween, a clamping structure to detachably connect the other ends of said members together to clamp said curtain portion therebetween, and means to mount said members on a window sash for movement therewith, said members being extensible to accommodate them to the width of the sash.

5. A device of the character described comprising a pair of clamping members each including extensible elements, means hingedly connecting said members together at one end, whereby when said members are spread apart a portion of a curtain or the like may be inserted therebetween, a clamping structure to detachably connect the other ends of said members to clamp said portion therebetween, said elements being extensible to fit the same to the width of said curtain or the like.

In testimony whereof I affix my signature.

CARRIE VAN WIE.
